UNITED STATES PATENT OFFICE.

MILTON L. DODGE, OF NEWBURYPORT, MASSACHUSETTS.

COUNTER STIFFENER.

Application filed May 25, 1918, Serial No. 236,497. Renewed August 15, 1922. Serial No. 582,070.

To all whom it may concern:

Be it known that I, MILTON L. DODGE, a citizen of the United States, residing at Newburyport, in the county of Essex and State of Massachusetts, have invented new and useful Improvements in Counter Stiffeners, of which the following is a specification.

This invention has relation to footwear and more particularly to turn shoes, and it has for its object to provide an improved counter stiffener for use therein, by the use of which a more perfect shoe may be produced.

15 On the drawing,—

Figure 1 shows a counter stiffener embodying the invention.

Figure 2 represents a vertical transverse section therethrough.

20 Figure 3 shows in section a partially completed shoe.

Figure 4 shows in section a completed shoe.

In the manufacture of turn shoes, the sole and the upper are lasted wrong-side out, and, by a suitable sewing machine, the two elements are sewed together, the stitches passing through the base of the channel flap. The sole is formed with a feather or reduced edge, and, when a molded counter stiffener is placed upright and secured on the sole, it rests upon the face thereof, so that a space is left between the heel-seat flange and the feather. Hence, when the 25 last is withdrawn and the shoe is turned, a relatively wide crack or "grin" is formed between the upper and the sole at the heel portion of the shoe. To overcome this serious objection to the use of molded counter stiffeners, especially in the manufacture of turn shoes, my improved counter stiffener is provided at the junction of the heel-seat flange and the upright or side wall thereof with a hollow downwardly-projecting rib 40 or bead to rest upon the feather or reduced edge.

On the drawings, a molded counter stiffener is shown, having an upright or side wall forming the wings 10, and a heel-seat flange 11, the ends of which may be lapped and secured together by a fastener as shown. At the curved line of junction of the said flange and the wall, and hence at the outer margin of said flange there is a continuous 45 downwardly-extending rib or bead 12, which, when the stiffener is upright, projects below

the raised face of the flange. In forming the shoe, the sole 13 (which is rabbeted to provide the feather or reduced edge of any desired thickness and the shoulder 141, and which has the usual channel and the channel flap 15) and the upper 16 including the lining are assembled inside-out upon the last 17, and, after the upper has been pulled over or otherwise stretched and temporarily lasted, they are sewed together by any suitable turn-shoe-sewing machine. The curved needle enters the channel, and the stitches 18 pass through the base of the flap and emerge at the corner formed by the feather 14 and the shoulder 141 of the sole, and draw the upper tightly into the corner and over the feather or reduced edge. After the sewing and the trimming operations are completed and while the last is still in the 50 partially formed shoe, the counter stiffener is placed upright on the face of the sole at the heel end, so that the bead or rib fits in and rests upon the feather (and the edge of the upper thereon), and the raised inner portion of the heel-seat flange rests on the face of the sole. Then, by suitable fastenings passed through the heel-seat flange into the sole, the stiffener is secured against dislocation. The last is now withdrawn and 55 the shoe is turned to enclose the stiffener after which the lining at the heel portion of the upper is overlapped upon the inner face of the stiffener, and is secured.

By the provision of the rib or bead at 60 the outer margin of the heel-seat flange, which is less in width than the feather and substantially equal in depth to the height of the shoulder, the stiffener is enabled to fit closely both on the feather and on the inner face of the sole, so as to leave no gap between the edge of the sole and the counter stiffener or between the edge of the sole and the upper. This feature of the invention is especially valuable in those shoes in which 65 a wooden heel is used, since the inflexibility of such heels accentuates the "grinning" at the heel end of the shoe when an ordinary molded counter stiffener is employed.

While I have described my improved 70 counter as especially valuable when used in the manufacture of turn shoes, I desire to have it understood that it may be also employed in the manufacture of McKay, welt or other footwear.

Having thus explained the nature of my 75 said invention and described a way of mak-

ing and using the same, although without attempting to set forth all of the forms in which it may be made or all of the modes of its use, what I claim is:

- 5 1. As a new article of manufacture, a molded counter stiffener, comprising a side wall, and an inwardly-projecting heel-seat flange integral therewith, the material of the flange adjacent said wall being de-
10 pressed to form a downwardly-projecting rib.
2. As a new article of manufacture, a molded counter stiffener, comprising a side wall, an inwardly-projecting heel-seat
15 flange integral therewith, and a downward-

ly-projecting rib positioned on the lower face of said flange near its outer edge and adapted to rest upon the inturned edge of the upper.

3. As a new article of manufacture, a 20 molded counter stiffener having a heel-seat flange formed with a downwardly projecting hollow rib at the outer margin thereof to rest upon the inturned edge of the upper, and with a raised inner portion 25 to rest against the inner face of the sole.

In testimony whereof I have affixed my signature.

MILTON L. DODGE.
